(57) **CLAIM**

The ornamental design for speaker support for a media player, as shown and described.

DESCRIPTION

FIG. 1 is a front perspective view of a speaker support for a media player showing our new design;

FIG. 2 is front perspective view thereof, with the door in an open position;

FIG. 3 is a rear perspective view of FIG. 1;

FIG. 4 is a front elevational view of FIG. 1;

FIG. 5 is a rear elevational view of FIG. 1;

FIG. 6 is a left side elevational view of FIG. 1, the right side being a mirror image;

FIG. 7 is a top plan view of FIG. 1;

FIG. 8 is a bottom plan view of FIG. 1;

FIG. 9 is a front elevational view of FIG. 2;

FIG. 10 is a left side elevational view of FIG. 2, the right side being a mirror image;

FIG. 11 is a top plan view of FIG. 2;

FIG. 12 is a bottom plan view of FIG. 2; and,

FIG. 13 is a rear elevational view of FIG. 2.

The broken line showing on the drawing disclosure is for the illustrative purposes only and forms no part of the claimed design.
